UNITED STATES PATENT OFFICE.

DAVID E. HUNTER, OF MUSKEGON, MICHIGAN, ASSIGNOR TO SHAW WALKER COMPANY, OF MUSKEGON, MICHIGAN, A CORPORATION OF MICHIGAN.

FIRE-RESISTING SAFE.

Application filed December 31, 1923. Serial No. 683,758.

To all whom it may concern:

Be it known that I, DAVID E. HUNTER, a citizen of the United States, residing at Muskegon, in the county of Muskegon and 5 State of Michigan, have invented new and useful improvements in fire-resisting safes as commonly used for housing and protecting valuable documents, records, etc., against loss or damage by fire, collapse of buildings, 10 and similar hazards.

A common kind of safe consists of a box-like portable case having an outer steel shell with a door-opening in one of its sides, an inner steel shell usually attached to the 15 frame of the door opening and spaced apart from the outer shell, a door having an outer and inner steel plate spaced apart from each other, the hollow spaces in the shell and door being filled or lined in whole or in part by insulating materials to retard the transmission 20 of heat from the exterior to the interior of the safe, and, while my invention applies more particularly to the type of safe using a solidified mortar like fill for its insulation, 25 I do not confine myself to that particular type in that many elements of my improved structure may be advantageously applied to other common types of safes using composition blocks, sheets or the like for insulation purposes.

Structures of the described kind are frequently used in public buildings where safes or other objects beyond a specified weight 30 cannot be placed on account of floor load and similar restrictions, and it being of great importance that safes in such locations should possess the best possible properties of resistance against fires and the hazards incident thereto.

40 I have accordingly devised novel means and structures in the manufacture of safes as hereinafter described, which provide a decrease in weight combined with an increase in fire resistance; to such a degree 45 that a radical improvement is effected in the relative properties of a safe structure including lower relative costs of production and transportation, and greater relative value in respect to service to the public than 50 has been obtained under prior practice.

In respect to the resistance of safes against fire there is a generally accepted idea in the industry, that the steel flanges of a safe door and its supporting frame, forming as

they do a highly conductive medium for 55 the inward transmission of heat at the door joints are the most vulnerable points in a safe for the rapid passage of heat to its interior; but I have discovered that this defect in the common safe is due principally 60 to their not providing any structural means to compensate for the extreme differences in temperature between the outer exposed and inner protected portions of its structure at the door joints; where under fire, the 65 difference in expansion sets up excessive opposing stresses, that cause injurious displacements between the door and shell and separation of adjacent structure from its protective insulation; permitting the comparatively free passage of heat to its interior.

70 I have accordingly devised new methods of construction as hereinafter described to compensate for temperature differences under fire, and prevent injuries to the structure as described above.

75 Other important features of my invention consist of novel devices to give greater comparative structural unity and strength to the safe by connecting its insulation structure to its steel structure in such manner as to make each "insulated safe door" and "each insulated safe shell" in practically 80 integral units having a reinforced arch 85 like contour to give greater transverse strength to all exterior walls of the structure.

85 My invention also provides novel means of connecting the exterior steel structure to the 90 insulation structure in such manner that when the exterior shell of the safe becomes expanded under fire, the insulation structure is held close to the steel structure at the door joints thus in the most efficient 95 manner retarding the conduction of heat through the steel into the safe interior.

95 In the drawings hereto annexed, which 100 illustrate an embodiment of my invention, the several figures show the details of my improved structure as follows:

100 Fig. 1 is a perspective view of a safe constructed in accordance with my invention.

105 Fig. 2 is a fragmentary horizontal cross section on line 2-2 of Fig. 1.

Fig. 3 is a fragmentary vertical section on line 3-3 of Fig. 1.

Referring to the drawings, the structure

comprises a safe body including substantially rectangular exterior metal plates or covers 8, 9, 10 and 11 forming its sides, back, top and bottom respectively. These 5 plates are preferably formed slightly convex as illustrated in somewhat exaggerated scale in the drawings. Front flanged members 12, 13, 14 and 15 form the frame of its door opening all being preferably welded 10 or otherwise joined together to form a box-like safe body with one open side.

On the interior of the open side of the safe, and forming the frame thereof, is a flanged frame 16 comprising an inwardly 15 extending web portion 17 defining the margin of the opening, an offset inner portion 18 and a connecting web 19 substantially at right angles to portions 17 and 18. This frame is secured to said front 20 flanged members by rivets, welding or the like.

A series of anchor plates 20 preferably 25 perforated are secured to frame 16, as for instance to portion 18 and extend inwardly and downwardly where they are embedded in the insulation 2.

A series of wire mesh reinforcements 21 are secured at their ends to the exterior 30 plates 8, 9, 10 and 11, and are bent inwardly at their center portions to extend into the body of the insulation 2. The latter is poured and set in one solid piece preferably 35 with reinforcing wire mesh as at 22, 23 arranged about the case independent of, and within the fixed reinforcements 21.

Air pockets 24, 24 are formed about the web portion 17 by the use of a fusible 40 filler or similar means that will run out through a suitable vent 25, at about 200 degrees F., thus leaving a free air space at 45 these points. Obviously such air spaces may also be formed by insertion of a suitable shield plate to keep the space free from insulation at the time the insulation is molded. The purpose of this space will presently appear.

The insulation 2 is poured in the metal shell constructed as described, with a suitable inner mold provided to form the inner 50 walls relatively thick along the edges or corners, and with slightly concaved intermediate surfaces, as illustrated in somewhat exaggerated scale in the drawing. The insulation thus encloses the fixed reinforcements 55 21 attached to the outer walls as described, as well as the reinforcing members 22 and 23.

When the insulation has properly set and 60 dried, the inner mold is removed, and the inner part of the body completed by insertion of suitable inner walls, or compartments as desired, as for instance, plates 26 and 27, suitably braced against the insulation and secured to the flanged door frame 16. A 65 series of anchor plates 28, 28 are also secured

to the metal frame adjacent the door opening, as for instance, to an extension 29 of web 18, and having a flanged portion 30 extending inwardly to engage an inwardly facing shoulder 31, formed by the enlarged 70 corner section of the insulation.

The door for the above described safe body comprises an outwardly arched or dished exterior plate 32 with an inwardly extending flange 33 bent back at 34 and secured to an offset inner frame 35, marginal to the exterior door plate. An interior plate 36 extends across the inner margins of the frame 35. Reinforcing wire mesh 37 extends across frame 35 and other wire mesh 80 reinforcements 38 are secured to the exterior plate 32. The insulation 3 is poured and formed in the door in a manner similar to that described in connection with the safe body, being formed with a concaved inner 85 surface and relatively thick edges to fill frame 35, but with air pockets 39 marginal to the door, as shown.

Any suitable form of interlocking flange construction may be provided to seal the 90 door and frame 13, as for instance, co-acting flanges 40, 41 and 42 may be employed intermediate frames 16 and 35.

The door is equipped with any suitable type of locking mechanism including a bolt 95 43 and is hinged at 44 to the case body in the usual manner.

The functions and purposes of the novel portions of my structure are as follows:

When a safe is exposed to the action of 100 fire and rapid rise in temperature causes a rapid expansion of its exterior steel shell, normally in a direction each way from the several median planes of its structure as indicated by the arrows E, E¹ on the drawings—and when this expansion is set up in the direction E as for instance, on the front door and frame 16 of my structure the several sides of the frame are free to 105 expand into the air pockets 24 and thus prevent fracture of the insulation structure adjacent to it, and the difference between the expansion of the outer steel structure in relation to the cooler interior steel structure is compensated by flexure of the free standing portion 17 of the frame 16 thus 110 preventing injurious distortions of the structures at these points.

The door plate 32, being subjected to the 115 same exterior temperature as the safe body expands with it and vital injury to the insulation structure is prevented by the air pockets 39 in conjunction with the free standing flange 33 which permits a rolling 120 expansion action at these points and a normal tendency to close up the door joint interior to same with a consequent stoppage of the passage of heat to the safe interior.

I do not confine myself to the sealing 125 flange construction shown to compensate 130

for the temperature differences, as any equivalent means to perform this function may be employed.

The normal expansions in directions E¹, 5 with reference to the protective insulation around the front frame of the shell is, in my structure, controlled by the anchor plates 20 and the angle plates 28 which hold and bond the insulation structure in close contact with frame 16 and further change the 10 normal direction of shell expansion to direction E², leaving the insulation in contact with the steel structure of the frame opening to keep it cool and thus retard the inward passage of heat at the door joints. 15

The purpose of the novel wire mesh reinforcements 21 is to give an integral bond between the insulation structure and exterior wall plate structure for greater strength 20 to resist the stresses of handling and transportation under normal temperatures, but the said reinforcements are preferably frangibly attached to the outer plates in such manner that they may be readily 25 sheared under expansion of excessive heat and leave the shell expansion under control of the several novel devices described above.

The principal purpose of the arched outer wall construction is to provide a safe structure giving maximum strength and resistance in relation to the weight thereof against external stresses or internal pressure as sometimes caused by the rapid expansion of air or insulation gases in its interior. 30

Having described my invention, what I claim as new, and desire to secure by Letters Patent is:

1. A fire resisting safe comprising a box-like body having metal side walls with rectangular marginal edges meeting at substantially right angles to each other, the central portions of said walls being convex with respect to said body, and insulating means in supporting engagement with the interior 45 surfaces of said walls.

2. In a fire resisting safe, a body having exterior walls, each wall structure comprising a substantially rectangular metal exterior member having its central portion normally convex with respect to said body, and structurally bonded with frangible reinforcing members to an interior molded insulation structure. 50

3. A fire resisting safe of the kind described, a body having exterior walls, each wall structure comprising a substantially rectangular metal exterior member normally structurally bonded with reinforcing members to said interior molded insulation 55 structure, said reinforcing members being readily frangible under excessive heat conditions.

4. A fire resisting insulated wall having a substantially flat exterior steel plate and 60 an interior insulation structure, and a plu-

rality of reinforcing members jointed to said plate to provide normal structural unity between said plate and its interior insulation, but readily frangible by shearing from said plate under differences in expansion of 70 said plate and insulation structure due to excessive heat conditions.

5. A fire resisting insulated safe, an exterior wall and insulating means normally in engagement therewith, a door frame, and rigid metallic retaining means extending inwardly from said frame to bond its insulation to said frame against expansion caused by the application of heat to its exterior structure. 80

6. In a fire resisting safe, a safe body having opening therein, a closure for said opening, said body comprising insulated walls having a metal cover extending inwardly adjacent said closure to form an insulated inner frame therefor, said cover having interior spaces free of insulation about the outer margin of said closure frame to permit lateral expansion of said closure relative to said safe body. 90

7. In a fire resisting safe, a safe body having an opening therein, a closure for said opening, said body comprising insulated walls having a metal cover extending inwardly adjacent said closure to form a frame therefor, said cover having a material having a relatively low melting point distributed interiorly about the margin of said closure frame, and means permitting escape of said material when melted, whereby lateral expansion of said frame is afforded relative to said safe body. 95

8. In a fire resisting safe, a safe body comprising an outer metal cover and interior insulation, a closure frame in said body having an interior metal wall formed continuous with said metal cover, a closure adapted to fit in said frame also comprising an outer metal cover and interior insulation, said closure and body frames having insulated inner portion contiguous to each other, and means at the outer marginal edges of said closure and frame permitting lateral expansion of the outer metal cover of said closure relative to the insulation within the cover of said safe body. 105

9. In a fire resisting safe, a body comprising outer convex metal walls and interior insulation in supporting engagement therewith, and a closure frame in said body comprising an inwardly extending metal wall formed continuously with said outer metal walls, and supported by insulation thicker than at intermediate portions of the body. 110

10. In a fire resisting safe, a body comprising outer convex metal walls and interior insulation in supporting engagement therewith, and a closure frame in said body comprising an inwardly extending metal wall formed continuously with said outer 115

metal walls, and supported by insulation thicker than at intermediate portions of the body, and rigid reinforcing means attached to said frame wall and extending inwardly 5 into said insulation.

11. In a fire resisting safe, a body comprising outer metal walls, insulation molded in engagement with said walls, a plurality of frangible reinforcements normally connected with said walls and extending into 10 said insulation, said reinforcements being frangible under excessive heat conditions, and independent reinforcing members extending through said insulation.
12. In a fire resisting safe, a body comprising outer convex metal walls, insulation molded in engagement with said walls, a plurality of frangible reinforcements con- 15

nected with said walls and extending into said insulation, and independent reinforcing 20 members extending through said insulation.

13. In a fire resisting safe, a body comprising outer metal walls, insulation molded in engagement with said walls, both said walls and said insulation being substantially 25 convex in cross section, a plurality of frangible reinforcements connected with said walls and extending into said insulation and independent reinforcing members extending continuously through said insulation on adjacent sides.

In witness whereof, I hereunto subscribe my name this 29th day of December, A. D., 1923.

DAVID E. HUNTER.
